UNITED STATES PATENT OFFICE.

EDWARD H. GOODRICH AND HENRY C. MARTINELLI, OF SPRINGFIELD, MASSACHUSETTS.

MOTION-PICTURE REEL.

1,389,500.

Specification of Letters Patent. Patented Aug. 30, 1921.

Application filed June 25, 1920. Serial No. 391,655.

To all whom it may concern:

Be it known that we, EDWARD H. GOODRICH and HENRY C. MARTINELLI, citizens of the United States, residing at Springfield, 5 in the county of Hampden and State of Massachusetts, have invented certain new and useful Improvements in Motion-Picture Reels, of which the following is a specification.

10 Our invention relates to an improvement in reels and more particularly to reels for use in connection with motion picture machines.

The principal objects of our invention are 15 to provide a reel having spring means for holding one end of a film or the like, so that said film may be easily and quickly attached to or detached from said reel; to provide means for operating said film holding means so as to eliminate the liability of the film holding means being distorted, as 20 frequently occurs when operated by the operator's finger; and to arrange the operating means so that it may be operated from one side of the reel, thus eliminating the 25 necessity of the operator cramping his hand between the two side plates to raise the film holding means.

Another object of our invention is to provide a reel that is simple in construction, 30 durable and efficient in use, and one that may be placed upon the market at a low cost.

Further objects of our invention will appear in the following detailed description, 35 taken in connection with the accompanying drawings, forming a part of this specification, and in which drawings:—

Figure 1 is a diagrammatic section 40 through our improved reel.

Fig. 2 is a vertical section taken on the line 2—2 of Fig. 1, and

Fig. 3 is a side elevation of our improved reel.

45 In the drawings, wherein similar characters refer to similar parts throughout the views, A designates the side plates or flanges; B, the hub portion secured between said side plates or flanges A; C, a leaf spring for holding the end of the film to be wound upon the reel; and D, the means for raising the film holding spring to a non-film engaging position.

50 In referring to the side plates or flanges, A, these members are of the ordinary con-

struction, having the usual openings 5 therein to reduce the weight thereof, and the central axial openings 6. At one side of and adjacent the opening 6 of one of the plates 5 is provided an opening 7 which 60 will be hereinafter more fully described.

The hub B has a central axial bore 8 therein that alines with the openings 6 of the side plates A. Adjacent and parallel to the bore 8 is provided a way 9 having 65 a reduced extension 10 at one end, and an enlarged opening 11 alining with the opening 7 of one of the side plates A, at the other end thereof. Radially extending from the way 9 to the outer surface of the hub 70 B, is provided a way or opening 12. These ways and openings just described are adapted to receive the means D for raising the material holding means C, which will be hereinafter set forth.

75 The means C for holding one end of the film or material to be wound upon the hub, consists of a leaf spring 13 conforming to the curvature of the hub B, and having one end thereof secured to said hub by screws 80 14, but any other securing means may be used if desired. It is to be noted that the leaf spring 13 extends over the small way 12 which will allow the means D for raising 85 said spring to engage the same. The free end of the spring 13 is adapted to be raised to allow the insertion of the material for clamping the same between said spring, and the said hub.

90 Referring now to the means D for raising the leaf spring 13, said means consists of a relatively large plunger 15, adapted to slide in the way 9. Said plunger is provided with an annular inclined face 16 tapering down to the reduced extension 17 95 which is adapted to slide in the reduced way 10. Slidably mounted in the way 12 is a pin 18 adapted to ride up the inclined face 16 when the plunger 15 is slid in the way 9. Thus the pin 18 will engage and raise the leaf spring 13. On the reduced extension near the inclined face 16, is a disk-shaped stop plate 19, which is adapted to bear against the pin 18 when a coil spring 20 returns the plunger to its non-raising position. The coil spring 20 is mounted upon the reduced extension 17 and is adapted to bear against the inner end of the relatively large way 9 and the disk shaped stop plate 19.

In assembling our improved reel, the plunger 15 is inserted into the way 9, thus the reduced extension carried by the plunger 15 will carry the spring 20 and will hold said spring in correct position while said reduced extension 17 enters the reduced bore 10. Pressure being exerted upon the plunger 15 until the disk shaped stop plate 19 passes the way 12 allowing the pin 18 to be inserted in the way 12, in rear of the stop disk shaped plate 19, said pin will be engaged by the disk-shaped stop plate and prevent the spring 20 from forcing the plunger 15 out of the way 9. After the pin 18 is assembled, the leaf spring 13 is secured over said pin, thus holding the pin 18 in the way 12.

When it is desired to insert one end of a film or the material to be wound upon the reel, between the spring 13 and the hub B the operator inserts his fingers through one of the openings 5 of both side plates A allowing one of his fingers to rest upon the plunger 15 while his thumb is on the opposite side of the reel, thus permitting the reel to be held in any desired position. By exerting pressure upon the plunger 15, the inclined face 16 will engage the pin 18, which in turn engages the leaf spring 13 and raises the free end of the same from engagement with the hub. The operator then inserts the end of the material between spring 13 and hub B and as he releases the pressure upon the plunger 15, the coil spring 20 returns the plunger until the disk shaped stop plate 19 engages the pin 18. In the meantime the leaf spring 13 has engaged the material and holds it firm.

Changes in details may be made without departing from the spirit or scope of our invention; but,

We claim:—

1. In a reel, the combination of a hub portion, a leaf spring secured to said hub portion for holding one end of the material to be wound upon said reel, a pin slidably mounted beneath said material holding spring, and a plunger slidably mounted in said hub portion having an annular tapered face adapted to engage said pin to raise said leaf spring to non-material engaging position.

2. In a reel, the combination of a hub portion, a leaf spring secured to said hub portion for holding one end of the material to be wound upon said reel, a pin slidably mounted beneath said material holding spring, a plunger slidably mounted in said hub portion having an inclined face adapted to engage said pin to raise said leaf spring to non-material engaging position, and a disk-shaped stop plate upon said plunger adapted to engage said pin to hold said plunger in said hub portion.

3. In a reel, the combination of a hub portion having a bore therein, a leaf spring secured to said hub portion for holding one end of the material to be wound upon said reel, a pin slidably mounted beneath said material holding spring, a plunger slidably mounted in said bore of said hub portion having an annular inclined face adapted to engage said pin to raise said leaf spring to non-material engaging position, a disk-shaped stop plate upon said plunger adapted to engage said pin to hold the plunger in said hub portion, and a coil spring adapted to engage against the inner end of said bore and said disk-shaped stop plate, to hold the annular tapered face out of engagement with the pin.

4. In a reel, the combination of a hub portion having a bore with a reduced extension therein; a leaf spring secured to said hub portion for holding one end of the material to be wound upon said reel; a pin slidably mounted beneath said material holding spring; a plunger slidably mounted in said bore of said hub portion including an inclined face adapted to engage said pin to raise said leaf spring to non-material engaging position, a reduced portion adapted to slide in the reduced portion of said bore, and a stop plate adapted to engage said pin to hold the plunger in said hub portion; and a coil spring mounted upon the reduced portion of said plunger and adapted to engage the inner end of the enlarged portion of said bore and said stop plate, to hold the inclined face out of engagement with said pin.

EDWARD H. GOODRICH.
HENRY C. MARTINELLI.
